(57) **CLAIM**

The ornamental design for a chair for 4D cinema, as shown and described.

DESCRIPTION

FIG. 1 is a perspective view of a chair for 4D cinema showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof; and

FIG. 7 is a left side view thereof showing the state in which the upper part and the front part of the chair for 4D cinema have been tilted during operation; and,

FIG. 8 is a perspective view thereof showing the state of operating.

The broken lines are for illustrative purposes only and form no part of the claimed design.
